UNITED STATES PATENT OFFICE.

EDWIN H. DODGE, OF HARTFORD, CONNECTICUT, ASSIGNOR TO THE HARTFORD TYPE-WRITER COMPANY, OF SAME PLACE.

ESCAPEMENT-FEED MECHANISM FOR TYPE-WRITERS OR ANALOGOUS MACHINES.

SPECIFICATION forming part of Letters Patent No. 643,403, dated February 13, 1900.

Application filed December 4, 1897. Serial No. 660,816. (No model.)

To all whom it may concern:

Be it known that I, EDWIN H. DODGE, a citizen of the United States, residing in Hartford, in the county of Hartford and State of Connecticut, have invented certain new and useful Improvements in Escapement Feed Mechanism for Type-Writing or Analogous Machines, of which the following is a specification.

10 This invention relates to escapement feed mechanism for type-writing and analogous machines controlled by the depression of a plurality of keys or equivalent parts; and it has for its main object the provision of mechanism for feeding the carriage of a type-writer evenly, smoothly, noiselessly, and without the shocks and jars usually incident to the operation of escapement mechanisms ordinarily employed in connection with machines of this 15 class. Moreover, it is my aim to provide such an escapement mechanism in which all of the parts shall be simple in construction, durable, effective in operation, and of low cost.

One of the main features of this invention 20 is the employment, in connection with the usual feed member or feed-rack of a type-writing machine, of an escapement member embodying two feed-dogs in fixed relation with each other, and so constructed and organized as to permit the rack or feed member to move forward in the usual manner step by step, while both of the feed-dogs remain immovable in the direction in which said feed-rack travels, the step-by-step advancing 25 movement of said rack being permitted solely by the movement of the feed-dogs in a direction transverse to that in which the rack travels. In the preferred construction these feed-dogs will be separated both longitudinally and transversely of their working ends, the longitudinal separation being for the purpose of spacing the dogs properly in the direction of their movement, while the transverse separation of such feed-dogs permits 30

40 the feed member or rack to advance a step or tooth and be stopped at the proper point by the second dog when the rack has been properly released by the first dog. These two feed-dogs just described are in fixed relation with 45 each other, and both of them will in the preferred construction be movable in the plane

of travel of the feed member or rack for the purpose of preventing injury to the dogs should the rack and the carriage of the machine be drawn back suddenly, as frequently happens. Thus, while employing two feed-dogs the positions of which are constant and do not require adjustment, I retain in the construction shown all of the manifest advantages resulting from the employment of an escapement device which is capable of yielding in the direction of the return movement of the feed-rack to avoid injury to these co-operative working parts.

In the drawings accompanying and forming part of this specification, Figure 1 is a rear elevation of a portion of a type-writing machine embodying an escapement feed mechanism constructed in accordance with my present invention and showing the parts in their normal idle positions. Fig. 2 is a sectional end elevation of the same as seen from the right in Fig. 1. Fig. 3 is a rear view similar to Fig. 1, showing the parts in the positions which they occupy when the escapement device is operated to permit the advance of the feed-rack one tooth. Fig. 4 is a view similar to Fig. 2, showing the parts in positions corresponding to those indicated in Fig. 3. Fig. 5 is a rear view similar to Fig. 1, showing the positions of the feed-dogs when the rack is drawn back suddenly while in contact with the dogs. Fig. 6 is an enlarged detail plan of the escapement device and its actuating means. Fig. 7 is a front view of the dogs and the rock-shaft on which they are mounted, as seen from the left in Fig. 2, and Fig. 8 is a perspective of the feed-dogs and the parts connected therewith.

Similar characters designate like parts in all the figures of the drawings.

In the drawings I have shown only so much of the type-writer frame and feed-rack as will suffice to illustrate the application of my improvements thereto.

The feed member which co-operates with the dogs may be of any suitable or usual type, but ordinarily will be in the form of a rack, such as R, having rigid teeth r of the usual type for co-operating with the feed-dogs. It will be understood, of course, that this feed-rack will normally tend to move forward in a

direction shown by the arrows in Figs. 1 and 3 under the stress of suitable actuating means—such, for example, as a spring properly connected therewith. (Not shown.)

5 A indicates, in a general way, a portion of the rear side of the frame of a type-writing machine of any suitable construction, and on this part of the frame the escapement device and its operating connections will be mounted. In the present case the frame has secured thereto in some suitable manner, as by means of screws, a bracket, such as B, from which rise two arms or uprights, (indicated by 15 and 15'), and between these arms the dogs of the escapement device may be mounted for oscillation substantially in the usual manner. In this case these dogs are intended to be carried by a rock-shaft of suitable construction—such, for instance, as that indicated by 10—this rock-shaft being removably supported between uprights 15 and 15', preferably by means of conically-pointed bearing-screws 16 and 16', extending through said bearings, with their conical ends seated in the cupped ends formed by corresponding conical recesses in the ends of such rock-shaft. This rock-shaft 10 has in this instance an opening 10" extending entirely through the enlarged portion 10' thereof, and in this opening the feed-dogs are intended to be mounted for oscillation. The rock-shaft may also have a transverse bore intersecting the side walls of the opening 10" for the purpose of receiving a pivot member, such as 17, on which the feed-dogs may be mounted.

As before stated, the essential feature of the escapement device forming the subject-matter of this invention consists in the employment of a pair of feed-dogs disposed in fixed relation with each other and preferably separated both longitudinally and transversely of their working ends, and while these dogs might be constructed and organized in a variety of different ways yet I prefer to make use of an escapement member substantially such as that shown herein, having two fixed dogs thereon with curved working ends, the curves of which are defined by an arc struck from a center in the axis of the rock-shaft 10. As the escapement member oscillates with this rock-shaft, the necessity of curving the working faces of the dogs will be apparent.

The escapement member which I make use of in this case is indicated by *e* and is preferably in the nature of a cam-shaped pawl, the smaller end of which (indicated by 20) is of such shape that the edges thereof will engage the opposite sides of the opening 10" in the rock-shaft and prevent turning of the pawl relatively to the rock-shaft during the oscillation of the latter. For the purpose of holding this pawl or escapement member in place I make use of the pivot-pin 17, to which I have hereinbefore referred.

In order that the escapement member may yield when the carriage is returned suddenly

and the rack is not raised from the dogs, I prefer that it shall be of the "movable" type and shall be returned to its normal position by a spring when the rack reaches the end of its retractive movement. The manner in which the member *e* is mounted will be apparent by referring to Fig. 7, from which it will be seen that said member is mounted for oscillation within the opening 10" at one end of the latter and that there is a clear space at one side of said pawl for permitting yielding thereof when the rack is returned in the manner just described. It will be noticed that one side of the member 20 is rounded off at 20' in order to permit the pawl to turn freely at such time.

Any suitable spring may be employed for maintaining the pawl in its normal upright position, (shown in Figs. 1 and 2,) while capable of yielding to enable the pawl to tip in the plane of movement of the rack, as shown in Fig. 5; but I prefer to employ a spring, such as that shown at 25, one end of which engages in an opening in the pawl in a suitable manner, while the other end is passed into a similar opening in the rock-arm by which the rock-shaft is operated. (See Figs. 2, 4, and 6.) Between the ends thereof the spring 25 may have a coil, through which will be passed a holding member, such as the set-screw 26.

In the construction illustrated herein the pawl or escapement member 20 has at the upper end thereof two feed-dogs, (indicated herein by 12 and 13, respectively.) One of these dogs is set preferably in advance of the other and in parallelism therewith and is separated from such other dog by an opening or space 14 for the purpose of enabling each dog when released from a tooth to move out of the way and allow the other to come into action. The space between the working ends of these dogs in transverse direction is of course for the purpose of permitting the escapement movement of the rack.

It will be noticed that in the construction shown the space between the two dogs 12 and 13 is less than a tooth-space and that as these dogs are in fixed relation with each other this interval is not variable, but always remains constant, thus assuring the proper coaction of the dogs with the teeth of a perfectly-formed rack and preventing tampering with the adjustment of these parts. The two dogs 12 and 13 are set in this case at opposite side edges of the escapement *e* and have straight faces at corresponding sides for engaging the straight edges of the rack-teeth and sloping faces at their opposite sides for engaging the oblique faces of said rack-teeth.

The rock-shaft 10, by means of which the escapement is controlled, may be operated in any suitable manner. In this instance I have shown projecting from said rock-shaft a rock-arm 10", pivoted to an arm 21, clamped to the upper end of the usual actuating-rod 22, which ordinarily will be controlled by a uni-

versal bar operated by the key-levers of the usual type-writing machine. (Not shown.) This arm 21 may be removably secured to the rod 22, said arm having in this case an opening therein through which such rod is passed and also having a clamping-screw 23 for securing the connecting-rod in position.

It will be obvious that by means of these parts my improved escapement device may be set in any proper position with respect to the rack, as the connection between the actuating-rod 22 and the rock-arm 10" constitutes an adjusting means for this purpose.

In the operation of my improved escapement feed mechanism—assuming the parts to be in positions shown in Figs. 1 and 2, with the straight face 13' of the dog 13 in position to engage and form a detent for the straight face of one of the teeth *r* of the feed-rack— the depression of the actuating-rod 22 will cause the escapement member to be oscillated from the position shown in Fig. 2 to that illustrated in Fig. 4. During this movement the dog 12 will be brought into the plane of the feed-rack, but will not become effective until said rack is released by the dog 13 slipping off from the edge of the tooth of the rack-bar, as shown in Fig. 4, whereupon the rack being released will move forward and the straight face of the next succeeding tooth *r* will be engaged and stopped against the corresponding straight face 12' of the dog 12. This movement does not, however, carry the feed-rack forward a distance equal to one full tooth-space, but only a portion of such distance, as will be clear by referring to Fig. 3; but when the actuating-rod 22 is released and returns to the position shown in Figs. 1 and 2 the face 12 will be released from the straight face of such succeeding tooth of the rack, and this straight face of the tooth will be stopped by the straight face 13' of the dog 13, whereupon the rack will have moved forward a distance equal to one full tooth-space. Hence it will be clear that on each depression of the actuating-rod and the release thereof the rack will be advanced one step by two partial movements, each of which partial movements is controlled by the oscillation of the pawl *e*, one such partial movement being due to the oscillation of the pawl from the position shown in Fig. 2 to that illustrated in Fig. 4, while the other is effected by the return of the pawl from the position shown in Fig. 4 to that represented in Fig. 2.

Owing to the fact that each feed movement of the rack is made up of two partial movements obtained in the manner just described and owing to the further fact that the two dogs are in fixed relation with each other and cannot change their relative positions the feed-rack is fed forward a precise distance at each actuation of the connecting-rod 22

by easy steps, and hence with but a slight shock on each release of the rock-shaft and 65 therefore with a minimum amount of noise. The manner in which the pawl is afterward swung on its pivot-pin 17 when the rack is returned quickly to its normal position without being elevated above the working ends 70 of the dogs is illustrated clearly in Fig. 5, from which it will be evident that no injury can result to the dogs by such return of the rack.

Having described my invention, I claim— 75

1. In a machine of the class specified, the combination, with a feed-rack the teeth of which are straight on one side and oblique on the other, of a feed-pawl oscillatory transversely to the feed-rack about an axis adjacent to said rack, said pawl embodying a pair of feed-dogs rigid therewith and each having a straight face coöperative with the straight faces of the rack-teeth, and each also having an oblique face coöperative with the 85 oblique faces of said rack-teeth, and each also having a working face defined by an arc struck from the axis of oscillation of the pawl, said dogs being separated transversely by a space sufficient to feed the rack a distance substantially equal to half a tooth-space at each movement of the pawl.

2. In a machine of the class specified, the combination, with a feed-rack the teeth of which are straight on one side and oblique 95 on the other, of a feed-pawl oscillatory transversely to the feed-rack about an axis adjacent to said rack and also yieldingly mounted to oscillate in the plane of the feed-rack, said pawl embodying a pair of feed-dogs rigid 100 therewith and each having a straight face coöperative with the straight faces of the rack-teeth, and each also having an oblique face coöperative with the oblique faces of said rack-teeth, and each also having a working 105 face defined by an arc struck from the axis of oscillation of the pawl, said dogs being separated transversely by a space sufficient to feed the rack a distance equal to half a tooth-space at each movement of the pawl. 110

3. In a machine of the class specified, the combination, with a feed-rack, of a rocker having an opening therein, and a feed-pawl oscillatory transversely to the feed-rack about an axis adjacent to said rack and yieldingly 115 mounted within said opening to oscillate in the plane of the feed-rack, said pawl embodying a pair of feed-dogs rigid therewith and separated transversely by a space sufficient to feed the rack a distance equal to half a 120 tooth-space at each movement of the pawl.

EDWIN H. DODGE.
